DECANTER

Donald R. Neil, Short Hills, N.J., assignor to Paul A. Straub and Company, Inc., New York, N.Y., a corporation of New York

Filed Nov. 13, 1964, Ser. No. 82,584

Term of patent 7 years

(D58—6)

I claim:

The ornamental design for a decanter, substantially as shown.
